UNITED STATES PATENT OFFICE.

FREDERICK JOHN TREVALLON BARNES, OF HAMILTON, NEAR BRISBANE, QUEENSLAND, AUSTRALIA.

HOSE CLIP.

Application filed January 6, 1922. Serial No. 527,452.

To all whom it may concern:

Be it known that I, FREDERICK JOHN TREVALLON BARNES, subject of the King of Great Britain, residing at Hamilton, near 5 Brisbane, Queensland, Australia, have invented certain new and useful Improvements in Hose Clips, of which the following is a specification.

This invention has for its object the production of a simple device for securing hose 10 on ferrules, metal tubes and the like.

In carrying out my invention I form a tension piece of suitable metal curved along one side to neatly fit against the outside of 15 the hose, being made of the smallest convenient size and thickness. This tension piece is adapted to fit over the ends of a piece of wire of suitable gauge and which is bent to fit around the hose. The clip is tightened 20 by means of a nut screwed on one end of the wire against the tension piece.

In order that my invention may be better understood I will now describe it with the aid of the accompanying drawings in 25 which—

Fig. 1 is a heavy type clip.

Fig. 2 is a plan thereof.

Fig. 3 is a light type clip.

Fig. 4 is a plan of a stamping for making 30 a stamped tension piece.

Fig. 5 is a view showing the formation of the wire.

Fig. 6 is a perspective view of a stamped tension piece.

35 The tension piece A is made of any suitable metal, either cast, stamped or machined.

In Figs. 1 and 2 the tension piece A is of heavy pattern for use on pipes of large bore and where heavy pressures are desired. The 40 tension piece A as shown in Fig. 3 is of a light type for use on small diameter pipe. The tension piece A as shown in Figs. 4 and 6 is stamped from strips of metal.

The inner side of the tension piece A is 45 curved to conform as nearly as possible to that of the circumference of the hose B to which it is to be fitted but of course it will be understood that it may be used for radii, approximating thereto. In one end of the tension piece A is formed a hole C and at the other end is formed another hole D and recess E. These holes C D are parallel, the hole C being tangential to the hose B. It is 50 possible that I may vary the shape of the hole D from that shown in the drawings.

In the case of the stamped clip (Figs. 4 and 6) the wire F passes through the slot C to the hole C.

For use in conjunction with this tension piece A is a piece of wire F of suitable gauge 60 curved to fit the hose B on which it is to be placed. One end G of this piece of wire F which is tangential to the curved portion is threaded to receive the nut H and the other end J is turned at right angles, and thus parallel to the threaded portion G being adapted to fit in the hole D and recess E. This band F may be round, oval or other sectional wire, formed at the ends, and plain or flattened at the part where it embraces the hose. 70 As an alternative, the band may be made of metal tape formed and shaped at the ends as may be necessary. It is preferred that the wire F should not be too hard, but such that can be readily bent. The nut H which sits 75 on the flat face K of the tension piece A may be of any suitable shape such as for use with a spanner or screw driver or may be milled or winged for use with the fingers and thumb.

When in use the wire F is placed round 80 the hose B to be clamped on the ferrule or the like. The tension piece A is then placed in position with the ends G H of the wire F in the respective holes C D and recess E of same.

The nut H is then screwed on the end G of 85 the wire F against flat face K of the tension piece A, and until sufficient tension is put on the wire F. It will be seen that as the nut H is screwed on the end G of the wire 90 F the diameter of the circle of wire is gradually decreased the wire F being pulled through the hole C in the tension piece A.

Having now particularly described and ascertained the nature of my said invention, 95 and in what manner the same is to be performed, I declare that what I claim is:—

1. In a hose clip, a tension piece having a portion thereof curved to conform with the contour of the hose and having openings in 100 the ends thereof, a hose embracing band having a curved portion and extended and substantially parallel ends engaging with the openings in the tension piece, one of the openings in said tension piece being disposed in a plane substantially tangential to the band and the other opening being disposed in a plane substantially radial of the curved portion of the band, and means for tightening 105 said band.

2. In a hose clip, a tension piece having a portion thereof curved to conform to the contour of a hose and having openings in the ends thereof, and a recess communicating with one of said openings, a hose embracing band having extended and substantially parallel ends, one end of said hose embracing band being received in one of the openings of the tension piece and the recess communicating therewith and the other end of the band being received in the other opening in the tension piece, the last mentioned opening being disposed in a plane substantially tangential to the band, and the first mentioned opening being disposed substantially parallel to the second mentioned opening, and means co-acting with said band and tension piece to clamp them about a hose.
3. In a hose clip, a hose embracing band curved to substantially conform with the contour of a hose having one end extended substantially tangential thereto and having the other end turned and extended in substantially parallel relation to the first mentioned end, a tension piece having separate

openings receiving the respective ends of the band, the turned end of said band preventing disengagement of the latter from the tension piece when applied to a hose, and means co-acting with the tangential end of the band to clamp the latter about a hose.

4. In a hose clip, a tension piece having a portion thereof curved to conform with the contour of the hose and having openings in the ends thereof, a hose embracing band having a curved portion and straight and substantially parallel ends engaging with the openings in the tension piece, permitting the latter to be slipped on and off of the ends of the band, one end of the band extending substantially radially and the other end tangentially of the curved portion thereof and means for tightening said band.

In testimony whereof I affix my signature in the presence of two witnesses.

FREDERICK JOHN REVALLON BARNES.
